Primary Examiner — Richard E Chilcot(74) *Attorney, Agent, or Firm* — Seyfarth Shaw LLP;
Brian Michaelis(57) **CLAIM**

The ornamental design for a helmet, as shown and described.

DESCRIPTION

FIG. 1 is a top perspective view of a helmet embodying our design;

FIG. 2 is another top perspective view of the helmet depicted in FIG. 1;

FIG. 3 is a side elevation view of the helmet depicted in FIGS. 1 and 2, with the opposite side elevation view being a mirror image thereof;

FIG. 4 is a front elevation view of the helmet depicted in FIGS. 1–3;

FIG. 5 is a rear elevation view of the helmet depicted in FIGS. 1–4; and,

FIG. 6 is a top view of the helmet depicted in FIGS. 1–5. The broken lines are for illustrative purposes only and form no part of the claimed design.

1 Claim, 6 Drawing Sheets(56)
